UNITED STATES PATENT OFFICE.

CHARLES L. LAWTON, OF HANCOCK, MICHIGAN.

MINE-SKIP LOADER.

1,415,181.

Specification of Letters Patent. Patented May 9, 1922.

Application filed June 8, 1921. Serial No. 475,866.

To all whom it may concern:

Be it known that I, CHARLES L. LAWTON, a citizen of the United States, and residing at Hancock, in the county of Houghton and State of Michigan, have invented a new and Improved Mine-Skip Loader, of which the following is a specification.

This invention relates to means for tipping-up mine skips so that they may be readily loaded, and its object is to provide manually controlled means whereby the mine skips may be caused to assume proper loading position at the desired loading station through the action of track sections which are moved into operative positions to receive the upper wheels of the skip after the lower wheels have passed such sections.

This invention consists, in combination with an inclined two-rail track on which four-wheeled mine skips are adapted to run, of auxiliary track sections normally out of the path of the wheels of the skips, but which are adapted to be moved into position to cause the upper wheels of the skips to move out from the main track so as to cause the skip to assume a more upright position.

It further consists in an arm adapted to swing in the path of the lower end of the skip and in mechanism connecting the arm and the auxiliary track sections whereby said arm, when swung by the lower end of the skip engaging therewith, moves the auxiliary track sections into the path of the upper wheels of the skip so as to cause such upper wheels to travel out from the main track.

It also consists in manually operable means for causing the control arm to hang in the path of the lower end of the skip so that the auxiliary track sections will be moved into the paths of the upper wheels of the skips.

It also consists in the details of construction illustrated in the accompanying drawings and particularly pointed out in the claims.

In the accompanying drawings, Fig. 1 is an elevation of mine timbering at a loading station and the skip controlling mechanism at that station. Fig. 2 is a plan of the skip controlling mechanism. Fig. 3 is an elevation of this mechanism on a larger scale. Fig. 4 is a similar elevation of a modified type of controlling mechanism. Fig. 5 is a plan of the track at the loading station.

Fig. 6 is a section on the line 6—6 of Fig. 5. Fig. 7 is an elevation similar to Figs. 3 and 4 of still another modified form of this device. Fig. 8 is a section showing the mechanism for swinging the auxiliary track sections. 60

Similar reference characters refer to like parts throughout the several views.

In deep mines, especially copper mines, the shafts are usually inclined and the ore carriers are usually rectangular skips having open upper ends with two wheels on each side. These skips are connected to the ends of wire cables which are wound up on great hoisting drums driven by powerful 70 engines. Indicators of various kinds show the location of the skips in the mine to the engineers on the surface so that the skips may be stopped at any desired level in the mine to be there loaded from the ore bins. 75 This work is often difficult when the angle of the track to the horizontal is not large and the mechanism shown in the accompanying drawings is designed to swing the skips to nearly vertical position so that the ore 80 may be freely discharged into the open upper end of the skip until it is properly loaded.

In Figs. 1, 2 and 3, I have shown the cross ties 1, stringers 2 and rails 3 as well as the 85 mine timbers 4. The ore bin 5 has a discharge spout 6 supported by the posts 7 resting on the side timbers 8 and 9. Braces 10 are shown extending from these side timbers to the stringers 2, but these timbers are 90 merely illustrative as they must be adapted to the various mine shafts and ore chambers. However, the braces 10 and side timbers 8 will usually be found desirable.

The skips 12 have an open upper end, a 95 bale 13 pivoted to the sides at 14 and connected to the cable 15, and side wheels 16 adapted to run on the rails 3. Auxiliary rails 18 are mounted on the pins 19 carried by the brackets 20 which are secured to the 100 braces 10. Boxes 23 attached to the side timbers 9 carry the shaft 24 on which the operating arm 25 is rigidly mounted. Attached to one end of this shaft 24 is a counterweight 26 to which is connected an operating device consisting of two parts 27 and 29 having a slideable engagement and a handle 28 at the upper end of the part 29 by which this counterweight may be lifted. 105

On the operating arm 25 is a pin 30 110

adapted to be engaged by the hooked arm 32 connected to the arm 33 attached to the shaft 34 mounted in the bearings 35 which are attached to the side timbers 9. A pair 5 of arms 36 connected to the shaft 34 connect to the counterweight ends 37 of the auxiliary rails 18 by means of the links 38. The operation of this device is as follows.

The counterweight 26 is sufficiently heavy 10 to hold the operating arm 25 in position shown in Fig. 1, when the skip can travel under it without contact, which is necessary when ore is being hoisted from lower levels. When the skip is to be loaded at the bin 15 shown in the drawings, the handle 28, rod 29 and counterweight 26 are raised by hand and the shaft 24 is turned and the arm 25 is swung until the pin 30 is engaged by the hooked arm 32, the arm 25 extending into 20 the path of the descending skip, the handle 28 being immediately released to permit the part 29 to slide down on the part 27 so that the handle 28 may be at the floor level where it will not interfere with the operation of 25 loading the skip. When the skip swings this arm to the position shown in dotted lines in Fig. 3, the pin 30 thereon pulls the hooked arm 32 to dotted line position and swings the arms 33 and 36 sufficiently to carry the 30 counterweight ends 37 of the auxiliary tracks 18 to the dotted line position shown in Fig. 3, the upper ends of these tracks 18 being brought into contact with the rails 3.

As indicated in Fig. 3, this occurs just 35 before the upper wheels of the skip reach these tracks 18, but when these wheels do reach these tracks, these upper wheels run out on these tracks, carrying the upper open end of the skip to position under the spout 40 6. At the same time the lower end of the skip swings in and comes to rest on the bumper 39. When the front wheels of the skip run onto the tracks 18 and the skip swings back the arm 25, the hooked arm 32 45 is disengaged by the arm which permits the counterweight 26 to swing the arm 25 out of the path of the skip.

When the skip is drawn up, the front 50 wheels run off the tracks 18 onto the rails 3, and the counterweights 37 of these tracks immediately swing them out of the paths of 55 the wheels of the skips. It is therefore possible to stop these skips at exactly the desired position at each loading station equipped with this controlling mechanism.

The details and proportions of this construction may be varied by those skilled in the art without departing from the spirit of 60 my invention as set forth in the following claims. Thus, instead of having the auxiliary tracks pivoted on horizontal pins supported by the braces 10, substantially horizontal beams 40 in Figs. 4 and 5 are shown extending from the braces 10 to the stringers 2. On these beams are the plates 41 hav-

ing inclined slots 42 through which the pins 43 extend. When these plates are moved to the right in Figs. 4 and 5, these plates are moved inwardly across the notches 44 in these beams 40 until the inner edges of these 70 plates are in alignment with the inner sides of the rails 3, at which point the ends of these plates rest on the rails. The operation of the control arm 25 is the same as before described, but the crank arm 46 extends 75 down from the shaft 34 and the links 47 are pushed toward the rails 3 whereas the link 38 is pulled away from the track. This movement of the track plates 41 occurs just after the lower wheels of the skip have 80 passed. The plates are returned in any desired manner, springs 48 being shown.

In Figs. 7 and 8 I have shown beams 50 extending from the braces 10 to the stringers 2 and these beams have notches 51 to 85 permit the skip wheels to pass. Plates 52 are hinged along their outer edges and are normally held vertical out of the paths of these skip wheels. Bell crank levers 53 are mounted on pivots 54 on the inner sides of 90 the beams 9 and connect to the crank arms 36 by means of the links 55 and to the arms 56 on the plates 52 by means of the links 57. The arms 36 are swung in the manner above described after the lower wheels of the skips 95 have passed the notches 51 in the beams 50, to bring the plates 52 down flat onto the beams 50 and with their adjacent ends resting on the rails 3. As soon as the skip has started up, the arms 25 swing down and 100 permit the plates 52 to be swung up to the position shown in Fig. 8, either by the weight of the links 57 and arms 56 or by the lower wheels of the skip.

I claim:—

1. In combination with the main rails of an inclined track for four wheeled skips, an operating arm adapted to swing into the path of a descending skip, a pair of auxiliary rails adapted to be positioned to extend at an angle to the main rails, and connections between the operating arm and the auxiliary rails to move them into the paths of the upper wheels of the skip when the actuating arm is swung by a descending 110 skip.

2. In combination with the main rails of an inclined track for four wheeled skips, an operating arm adapted to swing into the path of a descending skip, a pair of auxiliary 120 rails adapted to be positioned to extend at an angle to the main rails, connections between the operating arm and the auxiliary rails to move them into the paths of the upper wheels of the skip when the actuating 125 arm is swung by a descending skip, and means to normally hold the operating arm out of the path of the skip.

3. In combination with the main rails of an inclined track for four wheeled skips, an 130

operating arm adapted to swing into the path of a descending skip, a pair of auxiliary rails adapted to be positioned to extend at an angle to the main rails, connections between the operating arm and the auxiliary rails to move them into the paths of the upper wheels of the skip when the actuating arm is swung by a descending skip, a counterweight adapted to hold the operating arm out of the path of the skip, and manually operable means to move the counterweight to inoperative position.

4. In combination with the main rails of an inclined track for wheeled skips, a pair of auxiliary rails adapted to be positioned to extend in the vertical planes of but at an angle to the main rails to constitute a new track for the wheels of the skip, and means embodying an arm extending into the path of a descending skip to move the auxiliary rails to operative position.

5. In combination with the main rails of an inclined track for wheeled skips, a pair of pivotally mounted auxiliary rails adapted to be swung into position to extend in the vertical planes of but at an angle to the main rails, an operating arm extending into the path of a descending skip, and means connecting the arm to the auxiliary rails adapted to swing them into the path of the wheels

of the skip when said arm is swung by the skip.

6. In combination with the main rails of an inclined track for wheeled skips, a pair of pivotally mounted auxiliary rails adapted to swing into position to extend in the vertical plane of but at an angle to the main rails, a shaft extending transversely above the main rails, an arm mounted thereon, a weight to hold the arm elevated out of the path of the skip, manually operable means to render the weight inoperative to permit the arm to swing into the path of the skip, and means connecting the arm and auxiliary rails to swing them into operative position to receive the wheels of the skip.

7. In combination with the main rails of an inclined track for wheeled skips, a pair of auxiliary rails mounted to swing in the vertical planes of the main rails from substantially parallel to said main rails to engagement therewith, an operating arm extending into the path of a descending skip, and means connecting the arm to the auxiliary rails adapted to swing them into contact with the main rails to form a new track for the wheels of the skip when said arm is swung by the skip.

CHARLES L. LAWTON.
